UNITED STATES PATENT OFFICE.

CHARLES GOETZ, OF NEW YORK, N. Y.

CONTROLLER AND AIR-BRAKE HANDLE.

1,185,304.

Specification of Letters Patent. Patented May 30, 1916.

Application filed September 16, 1913. Serial No. 790,142.

To all whom it may concern:

Be it known that I, CHARLES GOETZ, a citizen of the United States, residing at the city of New York, borough of Manhattan, county and State of New York, have invented a certain new and useful Controller and Air-Brake Handle, of which the following is a specification.

This invention is a controller or air brake handle for use by motormen on the post of an electrical controller or the valve post of an air brake.

It is customary for the motorman engaged on electrically-propelled street rail-way cars, and other traction vehicles, to remove the handle or lever from the controller post or the brake valve post on each occasion when he leaves his station on the car. As a result of such frequent removal and application of the handle of one form or another to and from the post, the angular and rounded upper part of this post becomes worn to such an extent that the handles or levers of the different motormen who handle the car will not fit so tightly to the post as to obtain good results in the operation or control of the car, and, furthermore, it becomes necessary to repair the posts and to replace worn parts of the handles or levers, thus entailing labor and expense.

According to the present invention, the handle or lever is provided with a split bushing and with means for adjusting said bushing in order to secure a tight engagement between the bushing and the angular end of the post.

In a preferred form, the handle or lever is provided with a tapering socket, and the bushing is made tapering so as to conform to the socket, said bushing being split or divided lengthwise into a plurality of parts, preferably more than two. The means for adjusting is preferably a screw, mounted in a bearing on the handle or lever, said screw having a swiveled engagement with the divided bushing so that upon rotation of the screw the bushing will be moved endwise for tightening the handle or lever upon the post.

Other features and advantages of the invention will appear from the following detailed description taken in connection with the drawings.

In the drawings, Figure 1 is a side elevation, partly in section, illustrating my invention in connection with the handle and

post of an ordinary electric controller. Fig. 2 is a horizontal section taken on a plane above the post. Fig. 3 is a detail perspective view of one section of the divided bushing. 60 Fig. 4 is a side elevation partly in vertical section illustrating the invention in connection with the handle or lever for use on the post of an air brake.

Referring more particularly to Figs. 1, 2 65 and 3, A designates the post of an electrical controller, the upper part of which is angular in cross section at a, except that one side is slightly convex at a', this form of the post being usual or ordinary in the art. The post 70 is rotated by applying power to a handle or lever B which generally is of the kind used in prior devices, except as its construction is modified by the present invention. The lever is shown as having an ordinary 75 hand grip b and a depending lug b' adapted to serve the purposes of a stop. The lever is shown as having a recess c in which is fitted the end portion of a bracket C, said bracket having an arm c' in which is formed 80 a screw threaded opening, indicated by dotted lines at c''. The lever or handle is provided, furthermore, with a socket D, the walls of which are tapering. Socket D is angular in cross section, preferably square, 85 as shown in Fig. 2, and the inner surfaces or walls of the socket converge upwardly.

E designates a bushing which is angular in cross section and tapers in the direction of its length, said bushing conforming substantially to the contour of socket D. According to this invention the bushing is divided into a plurality of members e, the lines of division e' of the bushing being radial to the longitudinal axis thereof. It 95 is preferred to divide the bushing into four sections, although the number is not material, and these sections are arranged so that their side edges will not contact with each other, as shown in Fig. 2, whereby a certain amount of play is permitted to the sections of the bushing within socket D of the handle or lever. The members e are provided at their upper ends with flanges e² which extend toward each other, as shown 100 in Figs. 2 and 3, and at the meeting or adjacent corners of the flanges recesses are provided, which recesses constitute an opening whereby a screw F is adapted to pass into the bushing so as to have a swiveled engagement therewith. As shown, the screw 105 works in the threads of opening c² of bracket 110

C, said screw being thus mounted upon the handle or lever so as to be movable therewith. The screw is provided with a smooth portion f between collars f' , the smooth portion f of the screw fitting in the opening formed by the flanges e^2 of bushing members e . The collars f' engage with the upper flanged part of the bushing and these collars operate to rotatably connect the screw with the bushing so that rotation of the screw will impart sliding movement to the bushing within the socket. The divided bushing is retained in operative position by the swiveled connection with the screw and by engagement with the walls of socket D, as a result of which the parts of the bushing will not become separated accidentally, and the handle may thus be removed from post A or applied to said post A without separately adjusting the parts of the bushing. The screw may be of any desired dimensions, and for convenience in operation said screw is provided with a hand grip. In one form the hand grip is a knob F', shown in Fig. 1, whereas in another form the hand grip is a crosspiece F² shown in Fig. 4, the latter being provided with a central angular opening which fits on an angular upper end f^2 of the adjusting screw. The manner of using the device will be apparent from the foregoing description taken in connection with the drawings.

When a motorman leaves the car the screw F is turned in one direction for the purpose of sliding the divided bushing E within socket D, thus releasing the grip of the handle or lever upon post A, whereupon the handle or lever may be easily lifted off the angular end a of the post. When thus lifted off, the screw and the bushing remain attached to the handle without any liability of the separate parts constituting the bushing dropping out of the socket, for the reason that the collars of the screw retain the parts or members of the bushing within said socket. The handle or lever can be easily applied to the post by slipping the divided bushing over the angular end a of said post, after which screw F is turned in a direction to draw the members of the divided bushing into engagement with the walls of socket D, the taper of which forces the members e into tight engagement with the respective faces constituting the angular part a of the post. The handle or lever is thus applied firmly to the post by the simple and easy operation of the screw. With my device the wear and lost motion which takes place between the post and ordinary handles can be easily taken up by the adjustment of the divided bushing. It is not necessary to repair the lever or the post as is the case in ordinary devices. The screw is not in the way of the workman when manipulating the handle or lever, and said

screw affords an effective and desirable means for imparting the required adjustment to the divided bushing, although it will be apparent that other forms of adjusting devices may be substituted by a skilled mechanic. It will be noted that bracket C is secured detachably to the handle or lever by screws c^3 , and thus the bracket with the screw F may be dismounted from the handle. Obviously, the several parts of the new device may be taken off and replaced by other parts, thus facilitating repairs.

In Fig. 4 of the drawings the invention is illustrated in connection with a handle or lever b' for use on the post a' of an air brake. The lever is provided with the bracket C for supporting the adjusting screw F, said lever being also provided with socket D within which is positioned the divided bushing E, the said bushing and the screw being connected by a swivel, all as hereinbefore described; in fact, the air brake handle or lever is similar in all material respects to the lever for the electrical controller. In addition to the parts composing the invention, the air brake handle B' is provided with a locking dog G, the latter being provided with a stem g which is slideable in lugs g' of a bracket G', said bracket being secured rigidly to the under side of handle B'. On the stem of the dog is a coiled spring h which acts against a collar h' that is clamped on the stem g of the dog. The spring impels the dog normally into engagement with a notched part (not shown) usually provided on the air brake stand, but as such device is ordinary in the art, I have not considered it necessary to show the same.

It is apparent that the divided bushing and clamping screw of my invention will be used on the handle of an air brake with the same benefits and advantages as are pointed out in conjunction with the invention when applied to a controller handle or lever.

Having thus fully described the invention, what I claim as new, and desire to secure by Letters Patent is:

1. In a device of the class described, the combination with a post to be rotated, of a lever for rotating said post, said lever being provided with a tapering socket, a tapering bushing positioned within said socket, said bushing being expandable and being in frictional contact with the post and preventing said post from engaging the walls of said socket, and a screw swiveled to the bushing for imparting slidable movement thereto within the socket, said screw and the bushing being connected with the lever so as to be applicable therewith to the post and removable in a connected condition therefrom.
2. In a device of the class described, the

- combination of a post having quadrants, a lever provided with a socket of angular form in cross section, said socket tapering lengthwise, a bushing of angular cross section and tapering longitudinal section, said bushing being divided lengthwise and being positioned within the socket and said bushing comprising jaws adapted to grip the quadrants of the post and maintain said post out of engagement with the walls of said socket, and a screw swiveled to the bushing for imparting sliding movement thereto, said screw and the bushing being carried by the lever so as to be applied with the lever to a post to be rotated and to be removed in a connected condition from said post.
3. In a device of the character described, the combination with a quadrangular ended post to be rotated, of a handle to rotate said post comprising a socket provided with a removable split bushing to surround the quadrants of the post and to prevent said post from contacting the walls of the socket, and means coöperating with the handle and said socket to move said bushing longitudinally therein into and out of engagement with said post and adapting said handle to be removably secured to the post.
4. In a device of the character described, the combination with a post to be rotated having a rectangular end, of a handle to rotate said post comprising a socket provided with a removable bushing, said bushing being divided into a plurality of members each having an angular inner face and an inturned flange provided with a recess,
- whereby when the bushing members are positioned within said socket they are adapted to surround the rectangular end of the post with their side edges maintained out of contact with each other to present lines of division of the bushing at parts of the post other than at the angular corners thereof for the protection of the angular surfaces of the post, and means carried by the handle to extend through the recess of the bushing and engage the flanges of the bushing members to move the bushing longitudinally within the socket into and out of engagement with the post.
5. In a device of the class described, a controller handle having a socket tapering from the base of the handle toward the upper portion thereof, a detachable bushing comprising a plurality of angular members each of varying thicknesses, said members being provided with coöperating inturned flanges at the upper end thereof, and a threaded rotatable element mounted above said socket and having swiveled connection with the coöperating flanges of the bushing to move the bushing longitudinally with respect to the socket, said threaded rotatable element and said socket coöperating to maintain the bushing in operative position.
- In testimony whereof I have signed my name to this specification in the presence of two subscribing witnesses.

CHARLES GOETZ.
